UNITED STATES PATENT OFFICE.

CHARLES DE LUKACSEVICS, OF WEST NUTLEY, NEW JERSEY, ASSIGNOR TO GEORGE W. MORGAN, OF NEW YORK, N. Y.

INTERNAL-COMBUSTION ENGINE.

1,091,427.

Specification of Letters Patent. Patented Mar. 24, 1914.

Application filed December 13, 1911. Serial No. 665,509.

To all whom it may concern:

Be it known that I, CHARLES DE LUKACSEVICS, a citizen of the United States, residing at West Nutley, in the county of Essex and 5 State of New Jersey, have invented new and useful Improvements in Internal-Combustion Engines, of which the following is a specification.

This invention relates to improvements in 10 internal combustion engines of the double opposed cylinder type, and its objects are to provide an engine which shall be of relatively light weight in proportion to the degree of power developed and in which the 15 parts have a compact, well balanced, and advantageous arrangement.

An embodiment of the invention is illustrated in the accompanying drawings, wherein:—

20 Figure 1 is a sectional view mainly on the line F—F of Fig. 2, but including detail sectional illustration of the main shaft and its bearing; Fig. 2 is a sectional view mainly on the line A—B—C—D of Fig. 1, the upper 25 engine cylinder at the left of the figure being, however, shown in the plane of the line E—E of Fig. 1.

Similar characters of reference designate 30 corresponding parts throughout the several views.

The engine illustrated includes in effect eight cylinders, and for the purpose of this description, it is convenient to describe them as being arranged in adjoining groups of 35 four, the four cylinders comprising a group being disposed in a common vertical plane and the plane of one group being parallel to the plane of the other group. As the groups are precisely similar to one another 40 in respect of the arrangement of the cylinders and their appurtenances, it is sufficient to show, as in Fig. 1, the relation of all the cylinders of a group and, as in Fig. 2, the relation of the groups. With this general 45 statement of the nature of the arrangement and its illustration, Fig. 1 will be understood to illustrate in its entirety the group A, comprehending the cylinders at the left of the engine, and Fig. 2 will be understood 50 to illustrate the group A and also the group B, comprehending the cylinders at the right of the engine, only in so far as is necessary to disclose the relation which the two groups of cylinders bear to one another. The cyl-

inders of each group are arranged in opposition in upper and lower pairs, the axes of the cylinders of each pair being coincident, and parallel to the axes of the cylinders of the other pairs. Thus the upper pair of cylinders of the group A is indicated generally by the numeral 1, and the lower pair of cylinders of the same group by the numeral 2, while the upper pair of cylinders of the group B (of which only one cylinder is shown in Fig. 2) and the lower pair of cylinders of the same group (of which only one cylinder is shown in Fig. 2) are similarly indicated by the numerals 3 and 4 respectively. At this point it may be noted that the companion cylinders of each pair are 55 preferably, though not necessarily, formed integral with one another.

The several cylinders above referred to are provided at their outer ends with crank cases 5, which preferably have a rectangular cross section, as shown in Fig. 2, and carry bearings for crank shafts 6. Each crank shaft 6 is common to a pair of adjoining cylinders of the adjoining groups. Thus, the upper crank shafts are common to adjoining cylinders 1 and 3 at each end of the engine and the lower crank shafts are common to the adjoining cylinders 2 and 4 at each end of the engine. The groups A and B are spaced 60 from one another and the shafts 6 extend 65 across the interspace between said groups.

The pistons which work in the several cylinders are designated by the numeral 7 and are connected by pitmen 8 to the crank arms 9 of the shafts 6.

90 The interspace between the groups of cylinders is taken up by a casing 10 to which the cylinders are bolted and which comprises the parallel side plates 11 and 12 and the rim 13, the plates 11 and 12 and said rim 95 being connected together by bolt or screw fastenings 14. The said casing also carries bearings for the shafts 6, and said shafts are provided within said casing with pinions 15. Power is transmitted from the shafts 6 to a 100 main shaft 16, which latter, arranged centrally of the engine and at the same side thereof as the cylinder group B, projects through the side plate 12 and into the casing 10, being provided in said casing with 105 a relatively large spur wheel 17 with which the pinions 15 are in mesh. The plate 12 carries a roller bearing 18 for the shaft 16,

and additional bearings of similar or other character may be located as desired. By preference, the shaft 16 is hollow and the spur wheel is formed integral therewith. 5 Power is also taken from the shafts 6 for the operation of the inlet and exhaust valves. In the construction disclosed, which is of the four cycle type, an inlet valve 19 and an exhaust valve 20 are common to both cylinders 10 of each pair, 1, 2, 3, and 4, the valve 19 working with relation to an inlet chest 21 and the valve 20 working with relation to an exhaust chest 22. The valves 19 and 20 are arranged co-axially in opposed relation and 15 control a passage 23 which communicates with the compression space 24 between each pair of opposed pistons. The valves 19 and 20 are held in closed relation by springs 25, said springs being disposed in external pockets formed in the outer ends of the chests 21 and 22 and bearing against heads 26 which are provided upon the projecting outer ends of the stems of said valves. The valve chests 21 and 22 are suitably secured to the pair of 25 cylinders with which they are associated and are disposed in the common plane of the group of which said cylinders form a part and at the outer sides of the cylinders, that is, at the sides of said cylinders which are 30 the most distant from the shaft 16.

The casing 10 not only furnishes support or partial support for the crank shafts 6, but it also furnishes support for cam shafts 27 which are arranged transversely, parallel to the shafts 6. Each shaft 27 is operated by a corresponding shaft 6, the connections for this purpose comprising sprocket wheels 28 and 29 provided on the shafts 6 and 27 respectively, and a chain 30 connecting said sprocket wheels. The sprocket wheels 28 and 29 and the chain 30 are inclosed in the casing 10, the wheels 28 being located immediately adjacent the pinions 15. The shafts 27 are journaled in 45 bearings 31, which are suitably secured to the side plates of the casing 10 and project laterally from said casing. The bearings 31 carry at their outer ends small casings 32 which inclose the valve actuating cams 50 33. The heads 26 above referred to and which are provided on the outer projecting ends of the stems of the several valves, project into the casings 32 and are held in contact with the cams 33 by the springs 25. 55 Just as the shafts 6 are related to adjoining cylinders at each end of the engine, so the shafts 27 are related to the adjacent valves of said adjoining cylinders, as will be readily apparent, the cams 33 being provided 60 at both ends of the shafts 27 and acting upon the respectively adjacent valves which are associated with said adjoining cylinders.

The inlet chests 21 communicate with the inlet pipes 34 and the exhaust chests 22 65 communicate with the exhaust pipes 35.

Spark plugs 36 are located in the passages 23 to fire the mixture which is compressed between each pair of opposed pistons.

The crank shafts 6, of course, rotate in the same direction and for the purpose of positively providing against any blocking of the rotation of said crank shafts and consequent gear stripping, said crank shafts are arranged in slightly offset relation to the axial centers of the cylinders. Thus, in 75 Fig. 1, the line 37 indicates the axial center of the cylinders 1 and the numerals 38 and 39 indicate lines which intersect the axes of the shafts 6 and are parallel to and spaced from the line 37. The crank shaft 80 6 at one end of the engine is offset below the line 37 and the crank shaft 6 at the other end of the engine is offset above the line 37. The same relation of the crank shafts 6 and the cylinder axis 37 is shown 85 in connection with the cylinders 2 and is carried out in the cylinders 3 and 4 of group B. The particular arrangement shown is selected with regard to a rotation of the pinions 15 in the direction of the arrow 40. 90

Each pair of opposed pistons act simultaneously in any stroke of the cycle, that is to say, the respective power, exhaust, induction, and compression strokes are simultaneously effected by each pair of opposing pistons, although the several strokes are taking place simultaneously and *seriatim* throughout all the pairs of companion cylinders. 95

The movable parts inclosed in the crank 100 cases, in the casing 10 and the casings 32, run in oil and are efficiently supported and balanced. All the working parts are inclosed and consequently are well protected against dust, moisture, etc. The arrangement of the cylinders and their appurtenances is very compact and the engine, as a whole, is relatively light in proportion to the power which it generates. 105

Having fully described my invention, I 110 claim:—

In an internal combustion engine, parallel groups of opposed cylinders, pistons working therein, each group comprising upper and lower pairs of opposing cylinders, 115 transverse crank shafts common to adjoining cylinders of the groups at the ends of the engine and operated by the pistons of said cylinders, opposed inlet and exhaust valves for each pair of opposed cylinders, 120 chests for said valves located in the plane of the group of which the cylinders which the valves control form a part, valve operating shafts, the valve operating shafts being parallel to the crank shafts and corresponding in arrangement thereto, a centrally arranged main shaft common to all the cylinders of the groups and extending transversely of the engine, a casing taking 125 up the space between the groups, the main 130

shaft projecting into the casing and the
crank shafts and valve operating shafts
projecting transversely through the casing,
gearing for driving the main shaft from
the crank shaft, gearing for driving the
valve operating shafts from the respective
crank shafts, both gearings being wholly
inclosed in the casing, valve operating cams
provided on the ends of the valve operating

shafts, and casings inclosing said cams and 10
secured to said first-named casing.

In testimony whereof I have hereunto set
my hand in presence of two subscribing
witnesses.

CHARLES DE LUKACSEVICS.
